UNITED STATES PATENT OFFICE.

GUSTAF ELLSTROM, OF FITCHBURG, MASSACHUSETTS, ASSIGNOR TO MARY ELIZABETH JOHNSON, OF FITCHBURG, MASSACHUSETTS.

HUB FOR BICYCLE-WHEELS.

SPECIFICATION forming part of Letters Patent No. 722,402, dated March 10, 1903.

Application filed October 19, 1896. Serial No. 609,344. (No model.)

To all whom it may concern:

Be it known that I, GUSTAF ELLSTROM, a citizen of the United States, residing at Fitchburg, in the county of Worcester and State of Massachusetts, have invented a new and useful Improvement in Hubs for Bicycle-Wheels, of which the following is a specification, accompanied by drawings forming a part of the same.

- 10 My present invention relates to the wheels of bicycles; and it has for its objects to provide means for protecting the ball-bearings from dust, to provide means for adjusting the ball-bearing cones, and to simplify the construction of those parts contained in the hub of the wheel, and these objects are secured by the construction and arrangement of parts as hereinafter described, and set forth in the claim.
- 15 20 In the accompanying drawings, Figure 1 represents in elevation a hub of a bicycle-wheel and the spindle upon which the hub rotates. Fig. 2 is a sectional view on line 2 2, Fig. 1; and Fig. 3 is an end view of one 25 of the ball-bearing cones.

Similar letters refer to similar parts in the different figures.

Referring to the drawings, A denotes a spindle upon which the hub rotates and which 30 is held in the slotted ends of a fork, (indicated by the broken lines A').

B denotes the hub, provided with flanges B' to receive the spokes of the wheel and having at each end annular ball-cups C, which 35 are crowded tightly into the ends of the hub B, with their edges C' flush with the ends B² of the hub. The ball-cups C are provided with openings concentric with the spindle A to receive the ends of a thin sheet-metal tube

40 D, which incloses an oil-chamber D', communicating at each end with the chambers inclosed within the ball-cup C and containing the friction-balls E. An oil-tube D² is held in the hub B and communicates with the oil-chamber D' and having its outer end closed 45 by the ball D³, which is crowded by the spring D⁴ against the interior flanges D⁵ of the oil-tube D².

The spindle A is provided at one end with 50 the right-handed screw-thread A² and at the

opposite end with the left-handed screw-thread A³, and the ends of the spindle are slotted at A⁴ to receive a screw-driver. Screw-threaded ball-cones A⁵ A⁵ are held upon the screw-threaded ends of the spindle A. The 55 ball-cones A⁵ A⁵ are provided with conical surfaces A⁶, flanges A⁷, a cylindrical portion A⁸, and a hub A⁹. The hubs A⁹ of the ball-cones are flattened on opposite sides, as at A¹⁰, Fig. 3, to receive the slotted ends of the 60 fork A', by which the ball-cones are held from turning. Washers F and nuts F' on the ends of the spindle A secure the slotted ends of the fork between the washers F and the shoulders A¹¹ on the ball-cones. The edges 65 C' of the ball-cups are provided with internal screw-threads C² to receive the screw-threaded flanges G' of the caps G, which are provided with milled edges G² and are screwed against the ends B² of the hub. In this way the ball-cups C C are held from being crowded inwardly by the pressure of the balls thereon. The caps G are provided with a central hole G³, which fit the cylindrical portion A⁸ of the ball-cones and close the ends of the hub, 75 thereby protecting the ball-bearings from dust. The nuts F' serve as check-nuts to hold the spindle A from rotating. By loosening the nuts F' the spindle A is released and can be readily rotated from either end by 80 means of a screw-driver. As the ball-cones A⁵ are held from rotating by means of the fork, the rotation of the spindle A in one direction will cause the ball-cones to approach each other, thereby tightening the ball-bearings, and the rotation of the spindle in the opposite direction will increase the distance 85 between the ball-cones and loosen the bearings.

The caps G are held by the screw-threaded 90 edges of the ball-cups C, so that the mutilation of the screw-thread can be remedied by the substitution of a new ball-cup and cap G without the loss of the entire hub, and as each of the ball-cups is independent of the 95 central tube D it can be readily removed and a new one substituted in its place instead of requiring the removal of the central tube, as is the case when the ball-cups are formed integrally with the central tube.

What I claim as my invention, and desire to secure by Letters Patent, is—

In a bicycle, the combination of a hub, a screw-threaded spindle held concentrically in said hub, ball-cups inserted in the ends of said hub and removable therefrom and provided with internal screw-threads, cones held upon said screw-threaded spindle and outside said ball-cups, a series of friction-balls held between said cones and said ball-cups annular caps bearing against the ends of said hubs

and having screw-threaded flanges engaging the internal screw-threads in said ball-cups, whereby said ball-cups are held from being crowded inwardly by the pressure of the balls ¹⁵ thereon, substantially as described.

Dated this 15th day of October, 1896.

GUSTAF ELLSTROM.
